UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

LEAD-VARYING MECHANISM.

1,347,789.

Specification of Letters Patent. Patented July 27, 1920.

Application filed February 15, 1918. Serial No. 217,322.

To all whom it may concern:

Be it known that I, FRIEDERICH MÜLLER, a citizen of the United States, residing at Hartford, in the county of Hartford and 5 State of Connecticut, have invented certain new and useful Improvements in Lead-Varying Mechanism, of which the following is a specification.

The invention is applicable to lathes, 10 milling machines and other machines which are used for cutting screw threads, and its principal object is to provide an improved mechanism by means of which the lead of the thread to be cut may be varied at will so 15 as to be greater or less than the nominal lead, which the machine would cut without the use of the said mechanism.

It is well known that a tap, thread gage or other threaded tool or device, which must 20 be hardened after threading, requires a thread having a lead which varies from the true nominal lead. This is necessary in order to compensate for the change in dimensions which takes place during hardening. Usually the lead must be in excess of the nominal lead by a few thousandths of an inch per inch, as, ordinarily, shrinkage takes place during hardening. The amount of shrinkage varies in accordance with the character of the metal and in accordance with the method of treatment, and it is therefore necessary for accurate work to predetermine, by test or otherwise, the amount of shrinkage which will take place under given 30 conditions and then cut the threads with a lead which is in excess of the nominal lead by an amount equal to the amount of shrinkage. In accordance with the invention, any desired variations in the lead within the limits of accuracy required for the closest precision work can be easily and quickly secured.

A mechanism embodying the invention may be in the form of an attachment adapted to be applied to a machine previously or separately constructed, or it may constitute a permanent part of a thread cutting machine. In the accompanying drawings I have shown two embodiments of the invention, each of them being a mechanism adapted to be applied as an attachment to a previously or separately constructed lathe. It will be understood, however, that the invention is applicable to machines other than lathes, and it will furthermore be under-

stood that the mechanism embodying the invention can be constructed as a permanent part of the machine instead of as an attachment therefor. The drawings, therefore, are to be considered merely as illustrative and 60 are not to be construed as defining or limiting the scope of the invention, the accompanying claims being relied upon for that purpose.

Of the drawings:

Figure 1 is a front elevation of a lathe having applied thereto a lead varying mechanism embodying the invention.

Fig. 2 is a front elevation, on an enlarged scale, of the lead varying mechanism.

Fig. 3 is a transverse sectional view taken along the line 3—3 of Fig. 2.

Fig. 4 is a plan view, partly in section, along the line 4—4 of Fig. 2.

Fig. 5 is a front elevation similar to Fig. 2 but showing another embodiment of the invention.

Fig. 6 is a transverse sectional view taken along the line 6—6 of Fig. 5.

Referring to the drawings, Fig. 1 shows a lathe of standard construction provided with a bed 1, a headstock 2, a tailstock 3 and a tool carriage 4 movable longitudinally along ways on the bed. A rotatable lead screw 5 is suitably connected with the carriage to move it longitudinally, and gearing 6 of any usual or preferred form is provided for driving the lead screw in timed relation with the rotation of the headstock spindle. Carried by the lathe centers is a blank A upon which are being cut threads having a lead 80 slightly differing from the nominal lead.

In operation, the gearing 6 is adjusted for turning the lead screw 5 at the proper rate to produce a thread of the nominal pitch 95 upon the blank. By means of the mechanism embodying the invention, which mechanism will now be described, the movement of the lead screw is varied in such a way as to cause the required variation in the lead 100 of the thread.

Ordinarily the lead screw of a lathe is held against longitudinal movement. When a mechanism embodying the invention is to be used, suitable provision must be made to 105 permit longitudinal movement. As illustrated, the lead screw extends through a bearing bracket 7 which ordinarily serves, in connection with suitable collars such as 8, to hold the screw against longitudinal 110

movement. The machine can conveniently be modified to permit longitudinal movement by cutting away one end of the bracket 7 to provide a slight clearance, as indicated 5 in the drawings.

As illustrated, the mechanism embodying the invention comprises a bracket 9 which is bolted or otherwise secured to the bed of the lathe. The bracket is provided with a horizontal longitudinal aperture in which is fitted a sleeve 10. The lead screw 5 extends through and has a bearing in the sleeve 10. The sleeve 10 and the lead screw are held against relative longitudinal movement, the 10 sleeve, as shown, abutting against one of the collars 8 at one end and against a collar 11 at the other end. The sleeve 10 is threaded near one end, as indicated at 12, and engages with a similarly threaded portion of the 15 bracket 9. It will be clear that this threaded engagement between the sleeve and the bracket will cause the sleeve on the lead screw to be moved longitudinally when the sleeve is turned.

20 In order that the sleeve 10 may be turned, it is provided with gear teeth 13 which mesh with a rack 14 carried by a transverse slide 15 mounted in the bracket 9. For moving the slide 15 there is provided a horizontal 25 taper bar 16 having a longitudinal groove 17 therein. A shoe 18 projects downward from the slide 15 and enters the slot 17. It will be obvious that, if the taper bar be inclined and be moved longitudinally, the slide 30 15 will be moved inward or outward, thus causing a rotative movement of the sleeve 10 and a corresponding longitudinal movement of the lead screw 5.

35 The taper bar 16 is carried by a longitudinal slide 19 mounted on a bracket 20, which is bolted or otherwise secured to the bed of the lathe. The taper bar is pivotally connected with this slide 19 and can be adjusted about its pivot to any desired inclination 40 in either direction. For securing the taper bar in adjusted position, there are provided bolts 21, 21 extending respectively through slots in the ends of the bar. These bolts are respectively connected with slides 45 50 movable in dovetail slots in the slide 19.

55 The slide 19 must be moved in timed relation with the rotation of the lead screw. As illustrated in Figs. 1 to 4, the following mechanism is provided for this purpose. Rotatably mounted in bearings in the bracket 9 is a short longitudinal screw 22 which is connected with the lead screw 5 by means of spur gears 23 and 24. A nut 25 60 engages the screw 22 and is connected directly with the slide 19 by screws, or otherwise, as indicated in Fig. 3.

65 From the foregoing description it will be clear that when the lead screw 5 is turned, a corresponding rotative movement is given to the screw 22, which in turn moves the

slide 19 longitudinally. The taper bar 16, through its engagement with the shoe 18, moves the slide 15 transversely, thus rotating the sleeve 10 and moving the lead screw 5 longitudinally. It is therefore clear that 70 the lead screw 5 is given a steady longitudinal movement which is definitely related to the rotative movement thereof. This longitudinal movement increases or decreases the net movement of the tool carriage thus 75 changing the lead. The extent of the longitudinal movement of the lead screw can be varied as desired, within the limits of the mechanism. When the taper bar 16 is placed in exact parallelism with the slide 80 19 there is no longitudinal movement of the lead screw. An inclination of the taper bar 16 in either direction causes a corresponding movement of the lead screw 5 in either direction and the extent of this movement 85 can be varied by changing the inclination of the taper bar.

90 When the mechanism is not to be used it is preferable, in addition to placing the taper bar 16 in parallelism with the slide 19, to directly lock the sleeve 10 against rotation. For this purpose the bracket 9 is provided with a vertical aperture adjacent the sleeve and in this aperture there is positioned a shoe 26 adapted at its lower end to 95 engage the sleeve. By means of a screw 27 the shoe may be forced downward into firm engagement with the sleeve, thus locking it against rotation.

100 If desired a scale, as shown at 28, can be provided for guidance in setting the taper bar 16. This scale can be arranged to indicate the settings necessary for predetermined increases and decreases in the resulting pitch.

105 The mechanism shown in Figs. 5 and 6 is similar to that shown in Figs. 1 to 4 except that the slide 19 is differently actuated. In this case the supplemental screw is omitted and the slide 19 has connected with it a horizontal rod 29 which is adapted to be connected at its other end directly with the carriage 4. In this way the slide 19 is moved in unison with the carriage and, inasmuch as the carriage is operated by the 110 lead screw 5, the results are the same as already described in connection with Figs. 1 to 4, except that the rate of movement of the slide 19 is considerably greater. This change in the rate of movement can be compensated for by changing the angle of the taper bar 16.

115 The construction shown in Figs. 1 to 4 is preferable when relatively long blanks are to be cut. The thread on the screw 22 is of 120 a finer pitch than that on the lead screw 5 and the result is that the slide 19 has a relatively short movement. This construction permits the carriage 4 to be moved through a considerable distance without ne- 125 130

cessitating a long slide 19 and a long support therefor. When shorter blanks are to be threaded, the construction shown in Figs. 5 and 6 can be used.

5 What I claim is:

1. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, gear teeth on the sleeve, a transversely movable rack engaging the gear teeth, and angularly adjustable longitudinally movable taper bar for moving the rack, and means for moving the bar in timed relation with the rotation of the lead screw.
- 10 2. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, means including a taper bar for rotating the sleeve, and means including a rotatable screw operatively connected with the lead screw for moving the bar longitudinally in timed relation with the rotation of the lead screw.
- 15 3. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, means including a taper bar for rotating the sleeve, and means including a rotatable screw operatively connected with the lead screw for moving the bar longitudinally in timed relation with the rotation of the lead screw.
- 20 4. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, means including a taper bar for rotating the sleeve, and means including a rotatable screw operatively connected with the lead screw for moving the bar longitudinally in timed relation with the rotation of the lead screw but at a rate slower than that of the tool.
- 25 5. An attachment for a threading lathe or similar machine, comprising in combination a rotatable sleeve engaging the lead screw and fixed against longitudinal movement with respect thereto, a fixed element having threaded engagement with the sleeve, means including a taper bar for rotating the sleeve, and means including a rotatable screw adapted to be operatively connected with the lead screw for moving the bar longitudinally in timed relation with the rotation of the lead screw.
- 30 6. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, means including a taper bar for rotating the sleeve, and means including a rotatable screw adapted to be operatively connected with the lead screw for moving the bar longitudinally in timed relation with the rotation of the lead screw.
- 35 7. The combination of devices for holding a rotatable blank and a threading tool in operative engagement, mechanism including a rotatable lead screw for moving the tool longitudinally, a rotatable sleeve engaging the lead screw and fixed against longitudinal movement with respect thereto, a fixed element having threaded engagement with the sleeve, means including a taper bar for rotating the sleeve, and means including a rotatable screw adapted to be operatively connected with the lead screw for moving the bar longitudinally in timed relation with the rotation of the lead screw.

In testimony whereof, I hereto affix my signature.

FRIEDERICH MÜLLER.
